UNITED STATES PATENT OFFICE.

CHRIS KNUTSEN, OF PORT TOWNSEND, WASHINGTON.

DESIGN FOR A GUITAR.

SPECIFICATION forming part of Design No. 26,043, dated September 15, 1896.

Application filed July 23, 1896. Serial No. 600,311. Term of patent 14 years.

To all whom it may concern:

Be it known that I, CHRIS KNUTSEN, a citizen of the United States of America, residing at Port Townsend, in the county of Jefferson and State of Washington, have invented certain new and useful Improvements in Musical Instruments, of which the following is a specification, reference being had therein to the accompanying drawing.

This design for a guitar is illustrated in the accompanying drawing, in which the figure is a perspective view of my design.

The leading feature in my design consists in the body having hollow arms curved gradually outward, then inward toward the finger-board, the end of said arm resting against the

finger-board near the head thereof. On the outer shell of the guitar a crescent is outlined centrally of the arm, and centrally of the body of the guitar two approximately heart-shaped figures are arranged.

Having fully described my invention, what I claim as new, and desire to secure by Letters Patent, is—

The design for a guitar substantially as herein shown and described.

In testimony whereof I affix my signature in presence of two witnesses.

CHRIS KNUTSEN.
